CLAIM

The ornamental design for a portable pool cleaning device, as shown and described.

DESCRIPTION

FIG. 1 is a perspective view of a portable pool cleaning device showing my new design;

FIG. 2 is a left side elevational view thereof;

FIG. 3 is a front elevational view thereof;

FIG. 4 is a top plan view thereof;

FIG. 5 is a right side elevational view thereof; and,

FIG. 6 is a rear elevational view thereof.

The undisclosed bottom view is plain and unornamented. The hose shown broken away in all views represents indeterminate length.
